DEVICE FOR MARKING FABRICS

Gabriel Christiaan Erasmus Keet, Florida, Transvaal, Union of South Africa

Application July 7, 1944, Serial No. 543,944
In the Union of South Africa August 31, 1943

9 Claims. (Cl. 33—1)

1

This invention relates to means or devices for use in marking textile and like fabrics or material with dots or indicating marks, or dotted or similar lines, preparatory to smocking the same. The material to be smocked ordinarily has such dots or indicating marks applied to it by transfer from a printed or prepared sheet.

The object of the invention is to devise and construct simple and efficient means which will obviate the necessity for the employment of such transfers, and by the use of which the material can be easily and quickly marked, as by a pencil or the like, with the dots or similar indicating marks.

According to the invention I provide a base or foundation plate, strip or member, upon which the fabric is laid or placed to be marked, the upper surface of which is corrugated or provided with a number or arrangement of preferably parallel and regularly spaced upstanding ribs or projections, so that when a pencil or the like is drawn across the fabric upon the plate or member, transversely of the corrugations or ribs, dots or marks are made on the fabric at the points where it lies upon the crests of the corrugations or the upper surfaces or edges of the ribs.

A ruler or straightedge is provided for ruling the line of dots on the fabric, and such ruler may be in one piece with or hingedly or resiliently attached to the base or foundation plate or a holder therefor, in such a way that the fabric can be laid upon the base or foundation plate or member and held in position thereon by pressure applied to the ruler.

A fixed or movable guide strip or part may be co-operatively combined with the ruling means to indicate the distance apart of the lines of dots being marked. Such strip or part may also, if desired, be used as an additional ruling means.

The corrugated or ribbed base or foundation plate or member may be detachably arranged in a holder to allow of plates or members having differently spaced corrugations or ribs being employed in such holder.

A practical form of the invention will now be described in conjunction with the accompanying sheet of drawings, in which the ruling means is shown constructed integral with a holder in which a detachable base or foundation plate, strip or member is fitted; a guide strip also being shown movable upon and in relation to the ruling means. In the drawing,

Fig. 1 is a rear elevation of the device.

Fig. 2 is a plan of the same, and

2

Fig. 3 is a sectional elevation thereof on line $x-x$ of Fig. 2.

In the embodiment of the invention depicted the numeral 1 denotes the part or holder which serves to carry or hold the corrugated foundation plate, strip or member 2, and also to provide the ruling means 3 having a ruling edge 4. The part or holder 1 also holds or carries the guide strip or piece 5 which acts to indicate the distance apart of the lines of dots or short dashes being marked. The part or holder 1 may be made from a single piece of plate or strip metal of the requisite width which is doubled or bent so that the upper portion 6 thereof can lie above and substantially parallel with the lower portion 7. The lower portion 7, upon which the corrugated foundation plate or member 2 is arranged, is flat for the greater portion of its length. At or near the bend or fold the upper portion 6 is shaped or bowed to form a loop or space 8, in which surplus fabric or material, if the material to be marked exceeds the holder in width, can be placed after say rolling the same up at that side.

The corrugated foundation plate or member 2 is formed with lateral corrugations. It is constructed with a lug or flat projection 9 at each end, and the part or holder 1 is fashioned with slots or slits 10 through which the lugs or projections 9 project when the plate or member 2 is slid into position in the holder from the outside thereof. The parts 11, 12, of the holder 1 above the lugs or projections 9 are pressed upwardly to allow the lugs or projections 9 to lie flush with the lower flat surface of the holder 1.

The upper portion 6 of the holder 1 is cut or shaped for a suitable distance from the front edge, near both ends, as indicated at 13, and the central portion between the cuts 13 is bent inwardly beneath the remaining portion 14, as indicated at 15, to form the ruling edge 4 and expose portion of the upper corrugated surface 17 of the foundation plate or strip 2. The portion 14 is shaped to provide a depression 18 on the underside in which the bent or doubled portion 15 lies flush with the upper portion 6 at the ends thereof. The upper portion 6, due to the resiliency afforded by the loop 8, ordinarily is angularly disposed to the lower portion 7—see Fig. 1—but lies parallel therewith when pressed down to hold the fabric in position on the corrugated plate or strip 2.

The guide strip 5 is in the form of a longitudinally centrally folded strip of metal having bifurcated ends 19 in which frictionally engage the

portions 20 of the part or holder 1 beyond the cuts or edges 13. The portions 20 are pressed out upwardly slightly to form depressions 21 in which the lower portions of the ends 19 of the guide strip 5 lie flush with the bottom surface of the upper portion 6 of the part or holder 1.

In using the device the textile fabric or similar material is placed in proper position on the corrugated plate, strip or member 2 and the upper portion 6 of the part or holder 1 pressed down to hold the fabric firmly on said plate or strip 2. The line of dots is now ruled, as by a pencil passed quickly over the fabric and in engagement with the ruling edge 4. The guide strip 5 may be so set or arranged, by sliding it into the required position, that when either of its longitudinal edges 22 or 23 is on or near the ruled line of dots, the next line of dots to be ruled will be at the desired distance therefrom. The material to be marked can be moved within the device as it is marked, or alternatively said material can be pinned down or fixed upon a table or other surface and the device moved in relation thereto. If desired either or both of the edges 22, 23, of the guide strip 5 could be used as ruling edges.

Making the corrugated plate, strip or member 2 detachable permits of different corrugated or ribbed plates or members being inserted in the part or holder 1 having corrugations or ribs spaced at different distances apart, or providing different arrangements or patterns of dots.

What I claim as my invention and desire to protect by Letters Patent is:

1. Means of the nature indicated, including a member having a corrugated surface upon which the textile or similar fabric is laid to be marked by drawing a pencil or the like across it transversely of the corrugations, and a holder carrying such corrugated member and constructed with ruling means above said member.

2. Means of the nature indicated, including a member having a ribbed surface upon which the textile or similar fabric is laid to be marked by drawing a pencil or the like across it transversely of the ribs, and a holder carrying such ribbed member and constructed with ruling means above said member.

3. Means of the nature indicated, including a holder having a lower portion and an upper portion resiliently connected to said lower portion, and a detachable member having a corrugated upper surface and carried by the lower portion, upon which member the textile or similar fabric is laid and marked by drawing a pencil or the like across it transversely of the corrugations, said upper portion lying above the corrugated surface and being constructed to provide a ruling edge transversely of the corrugations.

4. Means of the nature indicated, including a holder having a lower portion and an upper portion resiliently connected to said lower portion, and a detachable member having a ribbed upper

surface and carried by the lower portion, upon which member the textile or similar fabric is laid and marked by drawing a pencil or the like across it transversely of the ribs, said upper portion lying above the ribbed surface and being constructed to provide a ruling edge transversely of the ribs.

5. Means of the nature indicated, including a holder having a lower portion and an upper portion resiliently connected to said lower portion, a detachable member having a corrugated upper surface and carried by the lower portion, upon which member the textile or similar fabric is laid and marked by drawing a pencil or the like across it transversely of the corrugations, said upper portion lying above the corrugated surface and being constructed to provide a ruling edge transversely of the corrugations, and adjustable guide means movable upon said upper portion which act to indicate the distance apart of the lines of dots or marks being made.

6. Means of the nature indicated, including a holder having a lower portion and an upper portion and a loop resiliently connecting said lower and upper portions, said upper portion being shaped to provide a space and a ruling edge at one side of said space, a strip member detachably connected to and carried by the lower portion of the holder and having parallel ribs on the upper surface thereof transversely of which the ruling edge is positioned, and an adjustable guide strip bifurcated at the ends and engaging at such ends with the upper portion of the holder at the ends of the space therein.

7. Means of the nature indicated, including a member having a corrugated base portion upon which textile or similar fabric is laid to be marked by drawing a pencil or the like across it transversely of the corrugations, an upper portion lying above said base portion and constructed with a ruling edge, and means resiliently connecting said base and upper portion at one end.

8. Means of the nature indicated, including a member having a corrugated base portion upon which textile or similar fabric is laid to be marked by drawing a pencil or the like across it transversely of the corrugations, an upper portion lying above said base portion and constructed with a ruling edge, and a loop resiliently connecting said base and upper portion at one end.

9. Means of the nature indicated, including a member having a corrugated base portion upon which textile or similar fabric is laid to be marked by drawing a pencil or the like across it transversely of the corrugations, an upper portion lying above said base portion and constructed with a ruling edge, and a loop resiliently connecting said base and upper portion at one end, and an adjustable spacing device, movable upon said upper portion, which acts to indicate the distance apart of the lines of dots or marks being made.

GABRIEL CHRISTIAAN ERASMUS KEET.
